UNITED STATES PATENT OFFICE

RUDOLF POPP, OF VALPARAISO, INDIANA, ASSIGNOR TO MCGILL MANUFACTURING COMPANY, OF VALPARAISO, INDIANA, A CORPORATION OF INDIANA

SWITCH MECHANISM

Application filed May 12, 1931. Serial No. 536,823.

My invention relates to a switch mechanism and more particularly to a connector device for actuating the switch mechanism.

In a socket or electric lamp switch it is customary to actuate the contact elements by a vertical movement of a lever or chain which is converted to a horizontal movement through a universal connection.

An object of the invention is to provide a new and improved universal connection.

A further object is to provide a simple and effective universal connection which is economical to manufacture.

A further object is to provide a universal connection which may readily and conveniently be assembled.

Other objects and advantages will appear as the description proceeds.

Referring to the drawing,

Fig. 1 is a plan view of a switch partially disassembled and embodying the invention,

Fig. 2 is a similar view with the cover and top plate of the switch mechanism removed,

Fig. 3 is a side elevation partly in section of a device embodying the invention,

Fig. 4 is a perspective view of a connector used in the device, and

Fig. 5 is a sectional view taken on line 5—5 of Fig. 3.

Referring now more in detail to the drawing, a switch mechanism is shown mounted between a pair of insulating plates 12 and 13 of any suitable insulating material, which are spaced apart and held in position by a pair of posts 14 and 15, which extend through the plates and are upset at their upper and lower ends to clamp the plates and hold them in position.

A U shaped member 16 is supported between the plates 12 and 13 and has projections adapted to extend into these plates to hold the member in position. This member has a round collar 17 attached to its end, and forms a fulcrum or pivot for a tubular lever 18. Collar 17 has an aperture extending through its center through which an arm or stem 19 projects. The end of stem 19 is provided with a head 21 and carries a U shaped pawl 22. The stem 19 is continuously urged to the left as viewed in Fig. 2, by a spring 23, one

end of which rests against the base of U shaped member 16, while the other end rests against the pawl 22. Pawl 22 engages a ratchet wheel 24 and upon reciprocation of the ratchet wheel a toothed contact bridging member 24 is rotated. This contact bridging member is provided with a plurality of teeth and alternate teeth are provided with conducting faces, all of which are electrically interconnected. Posts 14 and 15 support stationary contact member 26, which engage diametrically opposite teeth of the contact bridging member and in one position of the contact bridging member posts 14 and 15 are electrically inter-connected and in another position of this member the circuit between these posts is broken. Each of these posts is provided with a screw 27 for connecting an electrical conductor to the posts to place the switch mechanism in an electrical circuit. The switch mechanism thus far described is more fully disclosed in my copending application, Serial #512,836, filed Feb. 2, 1931.

In order to reciprocate the stem 19 and cause rotation of the contact bridging member, a connector 28 is pivotally connected to the stem 19 and secured within the tubular lever 18. The connector comprises a pair of arms 29—31 and a second pair of arms 32—33. The arms 29 and 31 are connected at their ends, and the arm 32 is connected to one end of arms 29 and 31, while the arm 33 is connected to the other end of arms 29 and 31. The lower end of arm 33 is formed into a loop 34 which passes through an aperture in arm 19 to provide a pivotal connection between the arm and the connector. In assembling this portion of the switch mechanism, the arm 33 is merely inserted through the eyelet or aperture in arm 19 and the end links of the ball link chain 35 are placed between the arms of the connector. The upper end of arm 33 is bent inwardly as shown at 36 to prevent the ball links from being withdrawn from the connector. The tubular lever 18 is then placed over the ball link chain as shown in Fig. 1. One side of the tubular lever is provided with a slot 37 and the lever is placed over the connector in such a position that the slot coincides in position with arm 32. As

the lever is forced over the connector, the arm 32 is pressed downwardly until the slot overlies the arm when the arm will spring into the slot and prevent separation of the connector 5 and tubular lever. If it is desired to dis-assemble the connector, all that is necessary is to depress arm 32 and withdraw the tubular lever from the connector. Heretofore it has been common practice to inter-connect the 10 connector and tubular lever by means of a set screw or the like, which requires a large amount of machine work in the manufacture of these parts. In accordance with the present invention, the lever mechanism may be 15 assembled without the use of any tools of any kind. The invention further permits the tubular lever 18 to be drawn from sheet metal. The upper end of the lever is provided with a cylindrical portion 38 which has an opening therethrough just large enough to receive a link of the ball link chain. The other end of this lever has an annular flange 39 provided with a cylindrical extension 41, which fits in an annular groove 42 in base 17. This 20 groove together with the fact that loop 34 extends into the aperture in base 17 prevents the lever from being laterally displaced and insures a pivoting movement of the lever when a tension is applied to chain 35. 25

30 It will be understood that the nature and embodiment of the invention herein described and illustrated is merely a convenient and useful form of the invention, and that many changes and modifications may be made therein without departing from the spirit and scope of the invention.

What I claim as new and desire to protect by Letters Patent of the United States is:—

1. An operating device for switch mechanisms comprising a tubular lever having a wall recess, a connector for attaching the lever to a switch mechanism adapted to be inserted into the lever from one end, and a spring catch for the connector adapted to snap into the recess to hold the lever and connector together.
2. An operating device for switch mechanisms comprising a tubular lever, a U-shaped connector for attaching the lever to a switch mechanism adapted to be inserted by the forked end into the lever from one end, said forked end being shaped to receive and hold a ball-ended chain when the connector is in the lever, and a spring catch for removably locking the connector and chain in the lever.
3. A pull chain connector for switch mechanisms comprising a tubular cap having a wall opening, a connector adapted to be inserted in the cap for receiving the chain at one end and connecting to the switch mechanism at its other end, and a spring catch for the connector adapted to snap into the wall opening to hold the connector and thereby the chain in the cap.
4. A pull chain connector for switch mech-

anisms comprising a tubular cap having a wall opening, a connector adapted to be inserted in the cap for receiving the chain at one end and connecting to the switch mechanism at its other end, and a spring catch for the connector adapted to snap into the wall opening to hold the connector and thereby the chain in the cap, said spring catch being pressable inwardly clear of the wall through said opening to remove the cap and chain from the connector.

5. An operating device for switch mechanisms comprising a universally operable tubular lever having a wall recess, a longitudinal connector for attaching the lever to a switch mechanism by one end and to hold a ball-ended chain in the other end when inserted in the lever, and a spring catch carried by the connector longitudinally thereof and adapted to snap into the recess when the connector is inserted in the lever, said catch having a free end edge engaging the recess whereby any operation of the lever is against said edge of the catch to correspondingly operate the connector.

In witness whereof, I hereunto subscribe my name this twenty-seventh day of April, 1931.

RUDOLF POPP.
